CLAIM

The ornamental design for the electrical connector, as shown and described.

DESCRIPTION

FIG. 1 is a front, left, and top perspective view of an electrical connector showing our new design;

FIG. 2 is a rear, right, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a second front, left, and top perspective view of the electrical connector, shown with environmental subject matters;

FIG. 10 is a third front, left, and top perspective view of the electrical connector of FIG. 9, shown in an alternate configuration with the environmental subject matters assembled;

FIG. 11 is a fourth front, left, and top perspective view of the electrical connector, shown with environmental subject matters;

FIG. 12 is a fifth front, left, and top perspective view of the electrical connector of FIG. 11, shown in an alternate configuration with the environmental subject matters assembled;

FIG. 13 is a sixth front, left, and top perspective view of the electrical connector, shown with environmental subject matters; and,

FIG. 14 is a seventh front, left, and top perspective view of the electrical connector of FIG. 13, shown in an alternate configuration with the environmental subject matters assembled.

(Continued)

The broken lines in the drawings depict portions of the electrical connector that form no part of the claimed design. Additional broken lines shown in FIGS. 9-14 depict environmental subject matters and form no part of the claimed design.

1 Claim, 14 Drawing Sheets
